UNITED STATES PATENT OFFICE.

CHARLES HOLLAND, OF CHICAGO, ILLINOIS.

FIRE-PLACE.

SPECIFICATION forming part of Letters Patent No. 258,922, dated June 6, 1882.

Application filed September 27, 1880. (No model.)

To all whom it may concern:

Be it known that I, CHARLES HOLLAND, of the city of Chicago, in the county of Cook, in the State of Illinois, have invented a new and useful Improvement in Open Grates and Open Fire-Places for Heating Apartments; and I do hereby declare the following to be a sufficiently full, clear, and exact description thereof to enable others skilled in the art to make and use the said invention.

My invention relates to that class of fire-places in which hollow metallic or earthenware forms, simulating wood or coal, as usually placed in open fire places or grates, are caused to appear as burning by means of jets of combustible gas or vapor issuing therefrom.

The nature of my invention consists in making such hollow perforated forms with a chamber or recess, either back of or beneath them, or both back and beneath, and placing in such recess or space a retort which generates gas or hydrocarbon vapors and passes them by suitable tubular connections into the hollow form, from which they burn with a heating and illuminating effect as they issue from the apertures.

I will now proceed to particularly describe the mode of making and using the said invention, referring in so doing to the drawings annexed and forming a part of this specification and the letters of reference marked thereon.

Figure 1 is a front elevation. Fig. 2 is a sectional elevation made in the plane indicated by the line $\alpha\alpha$ in Fig. 1. Figs. 3, 5, and 7, and Figs. 4, 6, and 8 are respectively front and sectional elevations of modified forms of this invention.

A represents a chamber or recess inclosed wholly or in part by the form B, consisting of hollow metallic earthenware or steatite or other refractory mineral shaped to resemble coal, wood, or peat in the usual shapes employed in open fire-places, and having numerous small perforations, (marked b .) This form B is preferably supported by a grate or hand irons, such as are used in ordinary fire-places. In the

lower part of the space A, I place a retort, C, preferably of one of the forms shown in my several Letters Patent dated May 21, 1878, and supply the same with liquid fuel under pressure by pipes D and valves d , most conveniently located, so as to pass in at the side of the fire-place through the wall E. A pipe, F, leading from the top of the retort C, terminates under the retorts C in a jet-tube, G, from which gas or vapor issues, which, on being ignited, beats the retort C. A pipe, J, extending from the retort C, leads the gas or vapor from the retort C to the hollow form B, from which it issues in jets from the small apertures b . A small pan, K, placed under the retort C and jet-tube G, receives a small supply of oil from a tube, d' .

The operation of this invention is as follows: Oil in the pan K from the tube d' , being ignited, heats the retort C and volatilizes the oil admitted thereto by the pipe D, and the resulting gas and vapor burn under the retort C and issue from the apertures b in the form B, produce luminous flame, the form B becomes heated, as do also the walls of the chamber A, and a radiation of heat from the form B, as well as the pleasing effect of the luminous flame issuing from the form, is maintained without dust or ashes and with a very small consumption of oil.

What I claim as my invention is—

1. The combination of a form, B, a retort, C, located behind, beneath, or within, and receiving heat radiated from said form and connected with a liquid-hydrocarbon-supplying tube, D, a heating-pipe, F, G, and a pipe, J, substantially as and for the purpose set forth.

2. The combination of the retort C, located in a chamber, A, within a form, B, simulating burning fuel, with the pipes J and F, as and for the purpose set forth.

CHARLES HOLLAND.
